Patented Dec. 28, 1971

222,782

SET OF BRIDGE PLAYING CARDS

Elisabeth Dibrell, 2553 Church St.,
Three Mile Bay, N.Y. 13693

Filed Sept. 11, 1970, Ser. No. 24,953

Term of patent 14 years

Int. Cl. D21—01

U.S. Cl. D34—13

Fig. 1.

Fig. 2.

FIG. 3.

FIG. 4.

FIG. 1 shows a plan view of a set of bridge playing cards, embodying the features of my new design.

FIG. 2 is a collective plan view of the individual bridge playing cards, separated from one another.

FIG. 3 is a plan view of a set of bridge playing cards, embodying a modification of the present design, the lettering being more removed from the edge of the card.

FIG. 4 is a collective plan view of the bridge playing cards, as shown in FIG. 3 thereof.

I claim:

The ornamental design for a set of bridge playing cards, substantially as shown and described.
